UNITED STATES PATENT OFFICE.

STEPHEN P. SOUTHARD, OF GENEVA, NEW YORK, ASSIGNOR TO C. C. POST,
OF SAME PLACE, AND HANNAH SOUTHARD, OF WATERLOO, NEW YORK.

SULKY.

SPECIFICATION forming part of Letters Patent No. 405,856, dated June 25, 1889.

Application filed November 19, 1888. Serial No. 291,290. (No model.)

To all whom it may concern:

Be it known that I, STEPHEN P. SOUTHARD, of Geneva, in the county of Ontario, in the State of New York, have invented new and useful Improvements in Sulkies, of which the following, taken in connection with the accompanying drawings, is a full, clear, and exact description.

This invention consists in a novel construction of a sulky in which superior rigidity is combined with minimum weight of the vehicle, the components of said sulky being so constructed and combined as to effectually brace the same, as hereinafter more fully described, and specifically set forth in the claims.

In the annexed drawings, Figure 1 is an inverted plan view of my improved sulky. Fig. 2 is a vertical transverse section on line *x x*, Fig. 1. Fig. 3 is an enlarged detached inverted plan view of the braces which stiffen the thill and prevent the axle-truss from being bent or deflected rearward or forward at its center by lateral strain exerted on the thills. Figs. 4 and 5 are detached perspective views of the interlocking parts of the metallic axle and one of the aforesaid braces; and Fig. 6 is a sectional view taken on line *y y*, Fig. 3.

Similar letters of reference indicate corresponding parts.

In my present invention I use a wooden axle-truss *A'*, with short metallic axles or axle-arms *A* secured thereto, in some respects similar to the sulky shown in my prior patent of October 7, 1884, No. 306,359. In the use of sulkies constructed according to said prior patent I discovered that the axle-truss became sometimes bent or deflected rearward or forward at the center and thus threw the wheels out of true tracking position when the thills were subjected to lateral strain.

One of the chief objects of my present invention is to overcome the aforesaid defect, and to that end I resort to the following construction and combination of parts.

The thills *TT* are mounted directly on the axle-truss *A'* and firmly bolted thereto and extend rearward therefrom, and the rear ends of said thills I unite by a cross-bar *D*, rigidly secured at its ends to the aforesaid ends of

the thills. To each end portion of the axle-truss I rigidly attach a lateral brace consisting of two arms *f f'*, formed in one piece, with an intermediate clip-tie *f'*, which latter lies across the under side of the end portion of the axle-truss, 55 and is fastened by a clip *g*, embracing the said portion of the axle-truss. One of the arms *f* extends forward from the axle-truss and has its extremity firmly fastened to the thill, and the other arm *f* extends rearward from the 60 axle-truss and has its extremity lying across the joint of the thill and cross-bar *D* and rigidly attached to the adjacent portions of said parts.

B represent braces, which are extended 65 from the axle-truss forward and from each other along the inner sides of the thills and secured at the front end to the thills and at their rear ends to the cross-bar *D* and intermediately to the axle-truss. Each of the 70 braces *B* I form of a wooden rail *b*, which is secured at its front end to the inner side of one of the thills and has its rear end framed to and abutting against the front side of the axle-truss, and lapping onto the latter end of 75 said rail and firmly secured thereto is a metallic extension *b'*, which is fastened to the under side of the axle-truss and has its rear end firmly attached to the cross-bar *D*. In order to obtain a more secure hold for the 80 brace *B* on the axle-truss, I form the inner end of the metallic axle-arm *A* with a mortise *a* extending across the same and midway the depth thereof, and the metallic brace-extension *b'* I form with a mortise *c* and seat it 85 with the mortised portion thereof in the mortise *a*, and thus cause the said parts to be effectually interlocked with each other, as illustrated in Figs. 4 and 5 of the drawings. The interlocked portions of the brace-extension *b'* and metallic axle-arm *A* are conjointly fastened to the wooden axle-truss by a clip 90 *h*, embracing the lower rail of said truss and having its shanks passing through the member *b'* and provided with nuts on the under 95 side thereof.

ll represent the stirrups on which the driver places his feet. Said stirrups I secure to the inner sides of the thills and outer sides of the wooden rails *b* of the braces *B*, and there- 100

by stiffen said parts and re-enforce their attachments.

It will be observed that by the braces B and f f', fastened to the axle-truss and to the 5 thills at the rear and front of the axle-truss in the manner described and shown, the liability of bending the axle-truss by lateral strain exerted on the thills is effectually obviated without materially adding weight to 10 the sulky.

Having described my invention, what I claim as new, and desire to secure by Letters Patent, is—

1. In combination with an axle-truss, the 15 thills attached directly thereto and extending rearward therefrom, a cross-bar uniting the rear ends of the thills, braces attached to the axle-truss and having their front ends extending from each other and along the inner sides 20 of the thills and secured with their front ends to the thills and at the rear ends with the aforesaid cross-bar, and stirrups secured to the inner sides of the thills and outer sides of the aforesaid braces, substantially as described and shown.

2. In combination with the axle-truss, the thills mounted thereon and extending rearward therefrom, the cross-bar D, uniting the rear ends of the thills, and the braces B B,

each composed of the wooden rail b, secured 30 at its front end to the inner side of one of the thills and abutting with its rear end against the axle-truss, and the metallic extension b', secured to the axle-truss and having its front end lapping onto and rigidly attached to the 35 aforesaid wooden rail, and the rear end of said metallic extension secured to the cross-bar D, substantially as described and shown.

3. In combination with the axle-truss, the thills mounted thereon and extending rearward therefrom, the cross-bar D, uniting the 40 rear ends of the thills, the metallic axle A, provided with the mortise a, and the brace B, having the metallic extension b', provided with the mortise c, and seated with the mortised portion in the mortise a and firmly secured to the axle-truss, substantially as set forth and shown.

In testimony whereof I have hereunto signed my name, in the presence of two witnesses, at 50 Syracuse, in the county of Onondaga, in the State of New York, this 15th day of October, 1888.

STEPHEN P. SOUTHARD. [L.S.]
